UNITED STATES PATENT OFFICE.

WILLIS A. INGALLS, OF CLEVELAND, OHIO.

KNITTING MACHINE.

1,144,846.

Specification of Letters Patent.

Patented June 29, 1915.

Application filed December 17, 1913. Serial No. 807,165.

To all whom it may concern:

Be it known that I, WILLIS A. INGALLS, a subject of George the Fifth, King of England, residing in Cleveland, Cuyahoga county, Ohio, have invented certain new and useful Improvements in Knitting Machines; and I hereby declare the following to be a full, clear, and exact description of the same, such as will enable others skilled in the art to which it appertains to make and to use the same.

My invention relates to yarn guide for knitting machines and its object, in addition to guiding the thread and opening the latch of the needle, as is customary in the ordinary form of yarn guide, is to produce a form of yarn guide in which the guide proper and the latch lifting point can be readily and independently adjusted to any desired position and also to prevent damage to the needles in riding over the latch opening point. These objects I accomplish by dividing the yarn guide into two separate parts each separately attached to the machine in such manner that it may be freely adjusted. To overcome the loss or breaking of needles when the needle rides over the latch lifting point, that part of the yarn guide carrying the lifting or opening point is separated from the second part or yarn guide proper by sufficient space to permit the needle falling back into place and the forward end of the yarn guide proper is so formed as to force the needle back into its ordinary path in the event it should be so sprung or otherwise damaged as not to fall back in the ordinary course.

In the accompanying drawings I show the invention in the form adapted to be used on a plate and cylinder machine.

Figure 1 is a plan view of the device showing a section of the needle plate, a section of the cam plate and showing the position of the yarn guide with the supports shown in dotted lines. Fig. 2 is a side elevation of the yarn guide proper with end view of the adjustable holder. Fig. 3 is a side elevation of the latch opening device showing the latch opening point and means for holding and adjusting the same. Fig. 4 is a bottom view of the yarn guide proper and Fig. 5 is a bottom view of the latch opening device. Fig. 6 is a side elevation of the holding block to be mounted on the cam plate and of the open end of the yarn guide proper and the adjust-

able holder therefor. Fig. 7 is a sectional end elevation on line X, X, Fig. 6.

A is the needle plate of the machine and a the needles mounted therein in the usual manner.

60

B is the cam plate.

C and D are holding blocks attached to the cam plate by the screws c¹, c², d¹, d².

E is a holder having its stem e adjustably mounted in the block C and having its head 65

bored to receive the stem G and is provided with a set screw E¹ for holding the stem G.

Secured to the lower end of the stem G is the needle evener I and on the upper side of

the latter is mounted the adjustable latch 70

lifter K which is secured to the needle evener I by the screw k¹. The latch opening point k is adjusted to the desired position by

means of the screws k¹, k² and k³. The stem 75

f of the holder F is mounted in a holding block D in the manner shown in Fig. 7.

The stem H of the yarn guide J is mounted in the head of the holder F and secured in the desired position by the set screw F¹.

The blocks C and D are mounted on the cam 80

plate B in approximately the desired position. To permit adjustment the holes C¹ and D¹ through which the screws c¹, d¹, pass

are of larger diameter than the screws, permitting the inner end of the blocks to be 85

shifted in either direction as may be desired. The stems e and f of the holders E and F 90

may be set to the desired position and there secured by the screws c and d. The needle

evener I and thread guide J may be adjusted 95

vertically or may be turned on the stem G and H and secured in any desired position by the screws E¹ and F¹.

In this manner it will be seen that the needle evener, the yarn 100

guide and the latch lifting point can be accurately adjusted to and rigidly secured in any desired position.

In actual operation the parts are adjusted substantially to the positions shown in the drawing Fig. 1 and Figs. 2 and 3. It will 105

be noted that with the parts in the relative positions indicated, the latches of the needles are prevented from closing from the time they are opened by the point k until they have passed the rear end of the yarn guide J.

The needle evener I passes under the inner 110

end of the needles, the latter sliding slightly up the inclined surface i of the needle evener, bearing against the upper surface of the

needle evener only sufficient to hold them in

needle evener only sufficient to hold them in

position to permit the point *k* to project underneath and raise the latch of the needle without coming in contact with the needle itself. The needles then pass under the yarn 5 guide *J* and the yarn passing through the groove *j* (Fig. 4) passes into the needle in the usual manner.

In the operation of knitting machines, the 10 needles often become more or less loose and occasionally become fouled with the latch lifting point and ride over the top of the latch lifter. In the construction here shown any needle so riding over the point would pass along the upper surface of the latch 15 lifter *K* and then drop in, or be forced down, between the latch lifter and the yarn guide thereby preventing damage to the needle by preventing its coming in collision with the 20 yarn guide.

Having described my invention, I claim:

1. In a knitting machine the combination of a latch opening point suitably attached to the machine with a yarn guide located 25 immediately behind said opening point and having its forward end beveled on the under side to engage needles riding over the latch opening point and force them to their original position for the purpose set forth.

2. In a knitting machine the combination 30 of an adjustable latch opening point, a yarn guide having its forward end beveled on the underside to engage needles riding over the latch opening point and force them downward and means for adjustably attaching said latch opening point and said yarn guide to the machine for the purpose set forth.

3. In a knitting machine the combination 35 of an adjustable needle evener suitably mounted on the machine, a latch opening

point mounted on said needle evener, and a 40 yarn guide having its forward end beveled on the under side to engage needles riding over the latch opening point and force them downward for the purpose set forth.

4. In a knitting machine the combination 45 of an adjustable needle evener suitably mounted on the machine, an adjustable latch opening point mounted on said needle evener, a yarn guide having its forward end beveled on the under side to engage needles 50 riding over the latch opening point and force them downward for the purpose set forth.

5. In a knitting machine the yarn guide *J* with its stem *H* secured in the holder *F*, said 55 holder being secured to the cam plate by the block *D*, screws in said holder *F* and block *D* for adjusting the holder and the stem *H* in combination with the needle 60 evener *I* with its stem *G* mounted in the holder *E*, said holder being secured to the cam plate by the block *C* and screws in said block *C* and holder *E* for adjusting said holder *E* and stem *G*, substantially as and 65 for the purpose specified.

6. A needle evener suitably attached to the machine, and a latch opening point mounted on the needle evener and secured thereto by the screw *k*¹ and adjusted by means of said screw *k*¹ and screws *k*² and *k*³ 70 substantially as specified.

In witness whereof I hereunto set my hand at Cleveland, Ohio, this 13th day of December, 1913.

WILLIS A. INGALLS.

In the presence of—

E. A. PETERS,
ALFRED CLUM.
